UNITED STATES PATENT OFFICE.

WILLIAM LEYLAND AND JOHN WM. LEYLAND, OF NEW YORK, N. Y.

LUBRICATOR.

No. 873,319.

Specification of Letters Patent.

Patented Dec. 10, 1907.

Application filed March 28, 1907. Serial No. 364,978.

To all whom it may concern:

Be it known that we, WILLIAM LEYLAND, formerly a subject of Great Britain, having declared my intention of becoming a citizen 5 of the United States, and JOHN WILLIAM LEYLAND, a citizen of the United States, both residing in the city of New York, borough of the Bronx, county and State of New York, have invented certain new and useful Im- 10 provements in Lubricators, of which the following is a specification.

Our invention relates to the class of oil or other lubricant cups or receptacles in which the lubricant is displaced by water of con- 15 densation resulting from live steam admitted to the receptacle through a channel which also serves as a means of discharge for the displaced lubricant, our present invention being an improvement upon that set forth in 20 our concurrent application Serial No. 305,204, filed March 10, 1906, and being designed to afford means for visually indicating the presence or absence of the lubricant within the receptacle. While applicable to the 25 class of lubricators generally, it is like the structure set forth in our said concurrent application, especially adapted to lubricators to be used in connection with rock drills, hoisting engines, and the like, where the 30 parts are subjected to rough usage.

The invention consists in the combination with a lubricator of the class designated, of an observation or tell-tale glass especially arranged and incased as hereinafter described 35 and claimed.

In the accompanying drawings, Figure 1, is a side elevation of our improved lubricator; Fig. 2, a top view of the same; Fig. 3, a sectional elevation upon plane of line 3—3 40 Fig. 2; Fig. 4, a sectional view upon an enlarged scale, of the tell-tale or sight glass taken at right angles to the section shown in Fig. 3.

The body of the oil receptacle or reservoir 45 A, is preferably made in one piece,—the top, bottom, sides and external protrusions for connections being cast integral, as will be understood by reference to Figs. 1 and 3, of the drawings, by which it will be seen that 50 the passage or conduit a , is formed directly within the base and side wall of said reservoir,—said conduit a , constituting and affording a passage for the inlet of live steam, and the outlet, simultaneously, of the oil to the 55 parts to be lubricated as in other lubricators of this class. The conduit a , extends to near

the top of the reservoir A, where it emerges through a valve seat a' , into a valve chamber having a lateral port a^2 , communicating with the interior of the reservoir.

60

A valve v , on the inner end of the threaded valve stem V is adjustable with relation to the valve seat a' ,—the male thread engaging a female thread formed for its reception in the casing and the stem V extending through a suitable packing box b , and being formed at 65 its outer end with suitable means for effecting its axial rotation to regulate the position of the valve v , with relation to its seat a' . In the drawings the upper end of the valve stem 70 is shown as of square form in cross section for engagement with a wrench or key, but any other well known mechanical expedient may be resorted to to effect the adjustment of the valve stem. We have herein shown a simple 75 form of valve and stem, for which however may be substituted that shown and described in our concurrent application for patent hereinbefore mentioned, or any other form which may be found most expedient.

80

E , is a screw plug for closing the opening f , through which the oil or other lubricant is supplied to the reservoir A; and d , is a drain passage closed by the screw plug or valve D. The drain passage d , opens through the bottom of the reservoir, which bottom is preferably made concave in form to facilitate the discharge of the water of condensation. While a separate plug may be used for the purpose, we prefer to utilize this plug E as a convenient means of applying our tell-tale or observation glass G, to the receptacle A. To this end we form said plug with an extension e , within which and the body of the plug is a bore e' , of sufficient diameter to receive the observation glass G, which fits the walls of the bore snugly so as to be supported laterally thereby. The inner end of the bore e' , terminates in an annular shoulder e^2 , through which opens a passage e^3 , of less diameter extending through the lower part of the plug C.

90

A perforated soft metal gasket m , is interposed between the lower end of the observation glass G and the annular shoulder e^2 ; and another unperforated soft metal gasket m' , is 105 interposed between the upper end of said observation glass and the screw plug E, by which the glass and gaskets are secured in position. Lateral sight holes s , s , are formed in the sides of the extension e , through which 110 the glass G may be inspected.

The pressure of live steam within the recep-

tacle forces the oil through the passage e^3 , and into the observation glass G, where it is held until the level of the water of condensation reaches the lower edge of the port a^2 —
5 and the lower end of the passage e^2 (these two points being on the same horizontal plane as shown in Fig. 3, of the drawings) when the escape of water of condensation with the oil between the level of the water and the top of
10 the receptacle draws off the oil from the observation glass to be replaced by live steam. This condition of affairs is readily detected by a glance through the sight holes s , s .

It will be seen that the plug C is made to
15 perform a double function in that it closes the filling port and affords a means of observation for detecting the presence or absence of oil within the receptacle. Furthermore in the construction shown the observation glass
20 is fully isolated and protected not only from contact with extraneous objects, but also against extremes of temperature, since only a small portion of the surface of the glass is exposed through the sight holes, the main
25 portion of the glass being inclosed and sustained by a metallic casing which maintains it at an even temperature. The structure is also simple and compact, and suited to the requirements and conditions of use of a lubricrator of the character designated, and is intended for and applicable only to a lubricrator in which the oil or other lubricant is displaced by the condensation of steam within the receptacle. Hence, otherwise than as above
30 set forth the operation is the same as heretofore set forth in our concurrent application herein previously mentioned,—the steam rising, in practice through the conduit a , passing between the valve seat a' , and the valve
35 v , when the latter is raised, and entering the reservoir through the lateral port a^2 . The condensation of the steam within the receptacle A causes the water of condensation to sink to the bottom thereof, thereby
40 displacing a corresponding amount of oil which flows through the port a^2 , spreading itself over the seat a' , and flowing down the sides of the passage a , in an annular stream through which the steam ascends centrally.
45 50 We have hereinbefore described the use of metallic gaskets in connection with the sight

glass, but we do not confine ourselves thereto since gaskets of other substances may be substituted with like result.

What we claim as our invention and desire 55 to secure by Letters Patent is,

1. In a lubricrator of the character designated, the combination with the lubricant receptacle having a common conduit for the inlet of steam and the gravitating outlet of 60 oil, of a tell-tale sight on top of the receptacle consisting of a glass tube and casing sealed at the outer end and communicating at the inner end with the interior of the receptacle, for the purpose described. 65

2. In a lubricrator of the character designated, the combination of a lubricant receptacle having a common conduit for the inlet of steam and the gravitating outlet of oil and a tell-tale sight consisting of a screw 70 plug fitted to the top of said receptacle and having a passage communicating with the interior thereof, a glass tube fitting in a bore in said plug and communicating with said passage 75 therein, said plug being formed with sight openings exposing said glass tube in part, and means for sealing the upper end of said glass tube for the purpose described. 80

3. In a lubricrator of the character designated, the combination with the lubricant receptacle having a common conduit for the inlet of steam and the gravitating outlet of oil of a tell-tale sight on top of the receptacle, consisting of a screw plug fitted to the top of said receptacle and formed with a passage 85 communicating with the interior thereof, a glass tube fitting in a bore formed for its reception in said plug and communicating with said passage therein, the plug being formed with sight openings exposing said glass tube in 90 part, a perforated gasket interposed between the lower end of said glass tube and the opposed supporting shoulder in the plug, a gasket interposed between the upper end of said glass tube and the screw by which it is secured in position, and said securing screw, 95 for the purpose described.
